US00D803789S

(12) **United States Design Patent** (10) Patent No.: **US D803,789 S**
(45) Date of Patent: ** *Nov. 28, 2017

(54) **CABLE MANAGEMENT RACK**

(71) Applicant: **Ortronics, Inc.**, New London, CT (US)

(72) Inventors: **Stewart A. Levesque**, Scotland, CT (US); **Lars R. Larsen**, Old Lyme, CT (US)

(73) Assignee: **Ortronics, Inc.**, New London, CT (US)

(*) Notice: This patent is subject to a terminal disclaimer.

(**) Term: **14 Years**

(21) Appl. No.: **29/521,474**

(22) Filed: **Mar. 24, 2015**

Related U.S. Application Data

(60) Division of application No. 29/427,964, filed on Jul. 24, 2012, now Pat. No. Des. 730,299, which is a continuation of application No. 13/180,778, filed on Jul. 12, 2011, now Pat. No. 8,526,181, which is a continuation of application No. 12/468,407, filed on May 19, 2009, now Pat. No. 7,983,038, which is a continuation-in-part of application No. 11/942,298, filed on Nov. 19, 2007, now abandoned.

(57) **CLAIM**

The ornamental design for a cable management rack, as shown and described.

DESCRIPTION

FIG. 1 is a perspective view of a cable management rack showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken lines shown represent unclaimed subject matter and form no part of the claimed design.

1 Claim, 6 Drawing Sheets
